UNITED STATES PATENT OFFICE.

JOHN McCLELLAND, OF WASHINGTON, DISTRICT OF COLUMBIA.

IMPROVEMENT IN FIRE-PLUGS.

Specification forming part of Letters Patent No. 44,439, dated September 27, 1864.

To all whom it may concern:

Be it known that I, JOHN McCLELLAND, of the city of Washington, in the District of Columbia, have invented certain new and useful Improvements in the Construction of Fire-Plugs or Hydrants; and I do hereby declare that the following is a full, clear, and exact description thereof, reference being had to the accompanying drawings, forming a part of this specification, and in which—

Figure 1 is a side elevation of my improved hydrant; Fig. 2, a vertical central section of the hydrant, with its feed and check valves shut and the hydrant-cover closed; Fig. 3, a similar view of the hydrant when uncovered and with its feed and check valves open. Fig. 4 is an obverse view of the front face-plate of the discharging chamber of the hydrant, showing the nozzle of the discharging-aperture and the handle of the check-valve therein; Fig. 5, a reverse view of the same plate, showing the position, arrangement, and construction of the check-valve closing the nozzle; and Fig. 6 is also a reverse view of the same plate, illustrating the operation of the check-valve when thrown open. Fig. 7 is an enlarged transverse sectional view of the handle and operating-crank of the discharge or check valve, showing the mode of combining them with each other and with the face-plate of the hydrant. Fig. 8 is an elevation of the operating-crank of said valve detached. Fig. 9 is a plan view of the curved guide, which holds the valve in its proper position, detached. Fig. 10 is an edge view of this guide, showing the projecting flange thereon, which is more clearly illustrated by the sectional view thereof in Fig. 11. Fig. 12 is an enlarged detached sectional view of the waste-valve of the hydrant when closed; Fig. 13, a similar view thereof when open, and Fig. 14 a plan view of the feed-valve.

Similar letters indicate like parts in each of the drawings.

My improved hydrant or fire-plug is constructed mainly of the hydrant proper, A, an inclosing-casing B, and a connecting elbow and valve-chest C, in combination with suitable feed and check valves, to be hereinafter more fully described.

The hydrant proper, A, is united to the elbow B, which connects it with the main water-pipe by means of a flange-joint secured by

bolts and nuts. It terminates upwardly in an enlarged square covered distributing-chamber, S, cast in one piece therewith, but having one of its sides open, to be closed by a detachable face-plate, D. It is surrounded and inclosed by a protecting-casing, B, formed in two longitudinal sections, and furnished with a cover, E, Figs. 1 and 2, which opens and swings over upon a hinge-joint in front of and below the detachable face-plate D of its distributing-chamber, so as to uncover and expose the top and three sides of said chamber, as clearly shown in Fig. 3 of the drawings. The upper portion of this casing is enlarged, so as to encompass the distributing-chamber and inclose the projecting nozzles J J. An annular flange, d d, formed upon the inner periphery of the enlarged portion of the casing, embraces the hydrant closely at a point just below the distributing-chamber. The two sections of the casing are fastened together around the hydrant by bolts and nuts fitting into lugs upon this interior flange, d d, and the entire case is secured in place by lugs or ears e e formed upon its lower end, so as to be held by two or more of the nuts a a, which clamp together the hydrant A and its elbow C, as shown in Figs. 1 and 2.

The flow of water through the hydrant is regulated by means of the feed-valve F, which moves in the upper end of the elbow, and is held or at pleasure drawn up against the lower end of the hydrant by means of the valve-rod G, extending up through the hydrant and into its distributing-chamber S.

An interiorly-screw-threaded sleeve, H, is screwed down a short distance upon the upper end of the rod G, and there firmly secured by a transverse rivet, as seen in Figs. 2 and 3. The remainder of the sleeve H projects above the end of the rod G, and serves as a socket to receive the end of the screw K, passing down through the center of the top plate of the distributing-chamber S, a boss, b, being cast upon the inner side of the top plate at this point to receive a brass collar, e, in which the shank of the screw K turns freely and loosely. This collar e is screwed into the top plate. The threads of the screw K terminate upwardly just below a narrow flange, f, which encircles the shank of the screw, as seen in Figs. 2 and 3. Between the lower end of the collar e and the flange f a suitable packing is

placed to prevent leakage at this point. Upon the upper end of the screw-shank a hand-wheel, M, is keyed and secured by a nut.

By turning the hand-wheel M the screw K, passing through the top of the chamber S, and working into the threaded socket H upon the upper end of the valve-rod G, will draw up or let down this rod and its attached feed-valve F, and cause said valve to cover or uncover the lower end of the hydrant, as illustrated in Figs. 2 and 3 of the drawings. An aperture, k, is drilled in the sleeve or screw-socket H just above the end of the valve-rod G, to permit the outflow of the water which may work its way down the threads.

The square distributing-chamber S of the hydrant is provided with three discharging-apertures formed, respectively, in the detachable face plate D upon the front of the hydrant and in the two adjoining sides of the chamber. Each of these discharging-apertures is fitted with a suitable nozzle, J, so formed as that hose or other discharging-pipes may be readily attached thereto. The inner opening of each nozzle is closed by a check-valve, L, at the end of the arm g, the end of the arm being so pivoted to the lower portion of the plate as to swing or slide over said nozzle in an arc having the pivot as its center. The valve is held closely against the inner end of the nozzle J and made to form a water tight joint therewith, by means of a guiding-arc, O, Figs. 5, 6, and 9, riveted to the plate, so as that a narrow flange projecting from its upper edge shall fit accurately in a receiving-groove cut in the edge of the valve, as shown in Figs. 2 and 3. As the valve swings upon its pivot i, its upper edge slides along upon the flange of the guiding-arc, and is supported and held thereby in a proper position.

The valve is opened and closed by means of a crank, N, whose shaft or axis h extends outwardly through an aperture formed in this face or side of the chamber at a point in a line passing through the centers of the nozzle-aperture and the pivot-pin i of the valve. Thus when the valve is closed the arm l of the crank lies under its extended arm g, between the inner face of said extended arm and the wall or side of the chamber. The pin m at the end of the crank projects through a curved slot cut in the offset n, formed upon the valve-arm upon its upper side, as illustrated in the drawings. The crank-pin m is so placed relatively to this slot in the valve-arm g as that when the arm of the crank coincides in its direction with a line drawn through the pivot of the valve L and the center of the nozzle J, it will be in the upper end of the slot, the valve being half open. If, now, the arm of the crank turn to one side or the other, it will push and swing the valve in that direction, but the lower end of the slot is so notched as that when the valve is either open or closed the crank-pin m will drop into this notch, and be thus brought to bear upon the valve in a radial direction against its pivot i, producing a complete lock

and so arresting its further movement. It will be noticed that when the pin thus drops into this notch in the slot it is so embraced thereby as that pressure upon the valve alone will not move it; hence when the valve is thrown open, it is held by the crank-pin m in such a manner as that the upward flow and pressure of the water thereon, however great, cannot close it. A simple movement of the crank in the proper direction will, however, unlock the valve by raising the pin m out of the notch or recess, and then, by causing it to bear against the opposite side of the slot above this recess, will force and carry the valve around and over the nozzle J until the crank-pin m, making a partial revolution, drops down again into the notch just as the valve has completely closed the discharging-aperture, as will be seen by reference to Figs. 5 and 6.

The crank N is operated by means of a lever or handle, P, which embraces the outwardly-projecting end of the axis h of the crank. A countersink is formed upon the outer face of the plate around the projecting end of the axis or shaft h of the crank. This countersink embraces an annular projection, r, formed upon the handle P of the crank, the inner face of this projection being beveled, so as to form, in connection with the bottom of the countersink, a packing groove or recess, which, when filled with suitable packing, renders the joint water-tight, and thus prevents leakage at this point. The handle P is keyed upon the axis of the crank and secured by a nut, q, as shown in Fig. 7, or by any other equivalent device.

The feed-valve F, which closes the lower end of the hydrant A, is formed mainly of two circular sections, s and t. The lower section, s, is formed with its lower face centrally convex and its upper side concave, as seen in the drawings, Figs. 2 and 3, and is larger in diameter than the upper section, t, which is made flat and uniform. The upper edge of the section s, projecting beyond the edge of the section t, is beveled, so as to fit accurately against the valve-seat w upon the lower end of the hydrant, and is faced with brass. A ring of lead is placed between the two sections of the valve. The brass facing of the valve extends back toward the center, so as to be clamped between the upper and lower sections thereof under the ring of lead. The valve-rod G passes centrally through the two sections s and t of the valve, and so secures and unites them as that they form one entire valve.

The valve F is kept from turning, and is guided in its movements by wings x x upon its lower section, s, which slide between ribs or ways y y.

The lower end of the hydrant-pipe is smaller in diameter than the upper end of the elbow C, in which the feed-valve F operates. The part projecting over is faced with a ring or washer, w, of india-rubber or its equivalent, so as to make the seat of the valve F water-tight. The india-rubber washer w,

forming the valve-seat at the lower end of the hydrant A, extends under so much of the flange upon this lower extremity of the hydrant as projects over the valve-chamber in the elbow, and is there covered and held in place by a ring of brass, against which the wings of the valve rest when the valve is closed.

I place a simple waste-valve, Figs. 12 and 13, in the lower end of the hydrant, to be operated automatically by the feed-valve F. This waste-valve consists of a tube, T, having a valve-rod, U, fitting closely therein. The upper end of the tube is enlarged interiorly to contain a spiral spring, V, and the upper end of the valve-rod U is made with a head, u, which fits accurately in the enlarged end of the tube T, preventing the rod from dropping down through the same. The spiral spring V is so confined in the upper end of the tube T as to press upon the head of the rod U and bear it down. A transverse aperture, W, is made through the tube, a short distance above its lower end and at right angles to its length. An annular semicircular recess, whose diameter is equal to that of the transverse aperture W, is cut entirely around the valve-rod U at a point which, when the power of the spring upon the head of the rod is not overcome, will be entirely below the transverse aperture in the tube. The valve-rod U projects such a distance below the end of the tube T as that the rod may be pushed up from below until the groove cut thereon shall coincide with the transverse aperture W in the tube. Hence, when the rod is pressed down by the spring V, the transverse aperture W is closed, as seen in Figs. 3 and 12; but when the resistance of the spring is overcome the opening through the same becomes complete, Figs. 2 and 13. This waste-valve is attached to the inner surface of the hydrant at such a point above the feed-valve F as that, when the feed-valve is closed, its upper surface will push up the end of the rod of the waste-valve just far enough to open the transverse aperture in the manner described. The offset Y of the waste-valve, through which the transverse aperture W is prolonged, is made to project through the side of the hydrant A, as represented in Fig. 2, and a discharging-vent is thus left, through which all water standing in the hydrant may flow out. When the feed-valve is opened to admit a flow of water through the hydrant, the rod U of the waste-valve is pressed down by its spiral spring V,

thereby closing the aperture, as shown in Fig. 3.

My improved casing B obviates the necessity of caps upon the nozzles J J, they being inclosed and protected by the cover E of the casing, as seen in Figs. 1 and 2.

Should any stones or other obstructions too large to pass through the discharging-nozzles pass the feed-valve and enter the body of the hydrant, they may be readily removed therefrom by taking off the detachable face-plate D, and allowing the water to flow unchecked through the opening thus formed.

The distributing-chamber S may be of any desired form and furnished with more or less discharging-apertures.

The cover may be secured, when closed, by any suitable locking device.

Having thus fully described my improved hydrant or fire-plug, what I claim therein as new, and desire to secure by Letters Patent, is—

1. The combination and arrangement of the inclosing-casing with the sides and top of a hydrant whereby the nozzle or nozzles of the hydrant shall be covered and protected when the hydrant is not in use, substantially in the manner herein set forth.
2. Providing each discharging-aperture of a fire-plug with an independent check-valve, substantially in the manner and for the purpose herein set forth.
3. The face-plate D, forming one side of the distributing-chamber S, arranged and combined with the said distributing-chamber, substantially in the manner and for the purpose herein set forth.
4. The combination of the curved ways or guides O O with the edges of the check-valves L L, when the said ways or guides O O are provided with flanges, which are received in grooves formed in the upper edge of the valves L, substantially in the manner and for the purpose herein set forth.

5. The arrangement and combination of the handles P with the valve-cranks N and the sides of the distributing-chamber S of my improved hydrant, substantially in the manner and for the purpose herein set forth.

In witness of this specification of my improved hydrant or fire-plug signed by me this 31st day of August, 1864.

JOHN McCLELLAND.

In presence of—

DAVID A. BURR,
H. KING.
